UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

LOCKER.

Application filed August 20, 1919. Serial No. 318,691.

To all whom it may concern:

Be it known that I, WALTER N. VANCE, a citizen of the United States, residing in Chicago Heights, in the county of Cook and

5 State of Illinois, have invented a new and useful Improvement in Lockers, of which the following is a specification.

This invention relates in general to lockers and has for its object broadly the provision 10 of an improved double door locker, i. e. a locker, the door opening of which is closed by two doors hinged at the two sides and swinging in toward each other into closed position.

15 A principal object of the invention is the provision of a double door locker providing a full opening when the doors are open and providing also for the secure fastening of the doors when in closed position and this 20 without danger of the door edges becoming separated.

Another important object of the invention is the provision of a locker of this character wherein the doors and latching device will 25 automatically arrange themselves in latched condition upon closing of the doors.

Another object of the invention is the provision of a locker of this character provided with a stop against which the edges of the 30 doors may be secured when the doors are closed, which stop will be movable with one of the doors to provide a full opening.

Another object of the invention is the provision of a locker in which the parts of the 35 latching or locking mechanism may readily be assembled and the parts may be readily individually replaced should occasion require.

Another important object of the invention 40 is the provision of an improved manipulating device for doors of this character together with effective means for locking the same.

Other objects and advantages of the invention will be apparent as it is better understood from the following description when considered in connection with the accompanying drawing illustrating a preferred embodiment thereof.

Referring to the drawings, 50

Figure 1 is a front elevation of a locker embodying my present invention;

Fig. 2 is a section taken substantially on the line 2—2 of Fig. 1;

Fig. 3 is a section taken substantially on the line 3—3 of Fig. 1;

Fig. 4 is a partial rear elevation of the door mechanism;

Fig. 5 is a section taken substantially on the line 5—5 of Fig. 1; 60

Fig. 6 is a section taken substantially on line 6—6 of Fig. 1; and

Fig. 7 is a perspective view of the keeper provided with the door manipulating devices. 65

For the purpose of illustrating my invention I have shown on the drawing a locker comprising a bottom wall 11, side walls 12 and a top wall 13 connected at the front by an angle iron door frame comprising a bottom angle 14, a top angle 15 and side angles 16. These angles are arranged in rectilinear formation, all having flanges arranged in the same vertical plane. The locker is provided with two doors 17 and 18 hinged or 70 pivoted respectively by hinges 19 to the sides or side members of this angle iron floor frame. The doors are of proper dimension to permit them to overlap when in closed position. Each is provided with a flange 21 at the pivot or hinge edge, which is bent in 75 to dispose the same behind the adjacent edge of the door frame as may be seen by comparing Figs. 1 and 2.

Each door is provided with top and bottom end flanges 22 for closing against the top and bottom members of the frame. The free edge of the door 18 having the outer overlapping edge is bent into an inturned flange 23 and the adjacent edge of the companion door is bent inwardly at 24 and then at 25 is bent back into parallelism with the plane of the body of the door to provide an offset flange 26 behind and extending beyond the flange 23 of the door 18. A latch 95 bar, in the present instance consisting of an angle iron 27, is slidably mounted upon the inner face of the door 18 and adjacent

its free edge. This bar is slotted at its lower end at 28 with an open-ended slot and at its upper end with a key-hole slot 29. Two rivets or pins 31 extend in from the 5 inner face of the door and engage within these slots to guide the latch bar in its movement.

The slots 28 and 29 are provided in the flange or part 32 of the latch bar and this 10 part of the latch bar has full face bearing against the door. The other part or flange 33 is provided with a locking lug 34 extending down beneath the lower end of the flange part 32. This lug is beveled at its 15 rear face at 35 to permit it to slide up over the lower member of the door frame in closing and is also slightly beveled at its forward face at 36 for drawing the door against the frame by engagement in a slot 20 37 formed in the horizontal part of the bottom member, and at an appropriate location. At the top the material of the flange part 33 is cut away, as indicated at 38, to provide a downwardly extending locking 25 lug 39 spaced from the part 32 of the latch bar. This upper lug 39 is adapted for engagement within a slot 41 of a keeper 42, which consists of a metal clip or sheet offset at 43 and having a part 44 adapted to lie 30 against the inner face of the vertical flange of the top angle of the frame, a rivet 45 being provided to hold this keeper or clip in place. The body 46 of the keeper is arranged inwardly an appropriate distance 35 for easy engagement by the lug 39 and to permit overlapping of the door edges as will be presently described. The lug 39 is beveled similarly to the lug 34, already described, at the bottom of the latch bar.

40 A manipulating handle or device 51 is positioned on the outer side of the door and this handle has a leg 52 provided with an extension 53 which is disposed through a slot 54 in the front wall. This extension 53 is also given the form of a latch lug and is fixed by a rivet 55 or otherwise to the outer face of the part 33 of the latch bar so that the two move together, and from certain aspects of the invention may be considered 45 to be a latching device. The lug 55 is provided with a hooked end 56 adapted to be engaged within a cut away recess 57 in the flange part 26 of the door 17.

It will be manifest from the foregoing 55 that the latching device is engaged with the top and bottom of the door frame, i. e. respectively by lugs 39 and 34, and also with the free or swinging edge of the door 17 by latch or lock 56.

60 The other leg 58 of the manipulating handle slides on the outside of the door and it is provided with a tail 59 which moves within a staple or keeper 61. The tail 59 is a mere flat extension of the handle and is 65 perforated at 62. The keeper or staple 61

consists of a metal strap bent to U-formation shown in Figs. 5, 6 and 7. The extremities of the strap are cut away at 63 to provide lugs 64 adapted to be thrust through a slot 65 provided in the door 18. 70 These lugs are then oppositely bent down as indicated in Figs. 5 and 6 to prevent the strap or keeper from being pulled out of position. The material of the strap is bulged or bent outwardly to provide protuberances 66 between and above the lugs. 75 These protuberances provide shoulders 67 for bearing against the outer face of the door and adapted to clamp the material of the door against the lugs 64 when said lugs 80 are bent as described.

Two lugs 70 extend respectively between the lugs 64 on each side of the keeper and are bent toward each other bringing the ends into toggle relation and spreading or tending to spread the legs of the keeper holding the parts firmly in assembled relation.

The keeper is also perforated at 68 to receive a lock 69. This lock when disposed through the perforations 68 and 62 prevents upward movement of the manipulating device and consequently prevents opening of the door.

In order that any marring of the finish 95 of the door by the sliding of the tail of the keeper may be confined to a space immediately beneath the keeper, I provide a raised rib 71 upon which the manipulating device slides in action.

It will be manifest that the latch bar acts as a door stop when the doors are closed as well as a lock bar and opening of the doors moves this stop out of position obstructing the full opening into the locker. 105 The latching device, moreover, not only secures the outer overlapping door edge to hold the doors closed but also insures the permanently closed relation of both of the two overlapping edges.

The latch bar is shown on the drawing to be provided with a recess 80 in the flange 32, this recess being provided for engagement with the locking bolt of a rim lock 110 should the provision of such a lock be desirable in particular instances.

It is thought that the invention and many of its attendant advantages will be understood from the foregoing description, and it will be apparent that various changes 120 may be made in the form, construction and arrangement of the parts without departing from the spirit and scope of the invention or sacrificing all of its material advantages, the form hereinbefore described being merely a preferred embodiment thereof.

I claim:

1. A locker, comprising in combination a door frame, a pair of doors hinged to the sides of said frame, one of said doors car- 130

- rying a latch bar engageable with the frame at the top and bottom and the other door intermediate its top and bottom.
2. A locker, comprising in combination, a door frame, a pair of doors hinged to the sides of said frame, one of said doors carrying a latch bar device having latching lugs for engaging the frame at the top and bottom and the other door intermediate its top and bottom.
3. A locker, comprising in combination, a door frame, doors hinged to the sides of said frame and having overlapping flanges at their meeting edges, and a latch bar device, carried by one of the doors, engageable with the top and bottom of the frame and engageable also with the flange of the other door.
4. A locker, comprising in combination, a door frame, doors hinged to the sides of said frame, a keeper secured to the top of the frame, and a latch bar slidably mounted on the door and engageable with the bottom of the frame and said keeper.
5. A locker, comprising in combination, a door frame, doors hinged to the sides of said frame, a keeper secured to the top of the frame, and a latch bar slidably mounted on one of said doors and automatically engageable with another door the bottom of the frame and said keeper on closing.
6. A locker, comprising in combination a door frame, doors hinged to the sides of said frame, and a longitudinally sliding latching device carried by the outer one of said doors for engaging the other.
7. A locker, comprising in combination a door frame, providing an unobstructed opening therethrough when the doors are open, doors hinged to the sides of said frame, and a central door stop carried by one of said doors and engaging the frame at the top and bottom when the doors are closed.
8. A locker, comprising in combination a door frame providing an unobstructed opening therethrough when the doors are open, doors hinged to the sides of said frame, and a central door stop carried by one of said doors and automatically engageable with the top and bottom when the doors are closed.
9. A keeper for a locker door and the like, comprising a U member having lugs for engagement with the inside of the door, and outwardly pressed shoulders between said lugs for engaging the outer face of the door.
10. A keeper for a locker door and the like, comprising a U member having lugs for engagement with the inside of the door, outwardly pressed shoulders between said lugs for engaging the outer face of the door, and means inwardly of said shoulders for spreading the parts of the keeper to hold the lugs and shoulders in holding relation to the door.
11. A keeper for a locker door and the like, comprising a U member having lugs for engagement with the inside of the door, outwardly pressed shoulders between said lugs for engaging the outer face of the door, and lugs beyond or inwardly of the shoulders and bendable in toward each other into toggle relation to hold the lugs and shoulders in holding relation to the door.
12. A locker, comprising in combination a door frame, doors hinged to the sides thereof, and a movable latch for securing the said doors to the top and bottom of the frames and to each other.
13. A locker, comprising in combination a door frame, doors hinged to the sides thereof and having peripheral flanges, said flanges engaging the doors at the hinged sides and at the tops and bottoms and engaging each other at the free edges of the doors when the doors are closed, and means for locking said edges together.
14. A locker, comprising in combination a door frame, doors hinged to the sides thereof and meeting at the center of the door frame, and a latching device slidably mounted on one door and having a part disposed beyond the outer face of said door for manipulation by the user and having parts also for engagement with the top and bottom of the frame and with the other door.
15. A locker, comprising in combination, a door frame, a door, a latching device slidably movable and carried by said door, a manipulative device disposed without said door, and means independent of said latch bar for guiding said manipulative device in its manipulating movement.
16. A locker, comprising in combination, a door frame, a door, a latching device slidably movable and carried by said door, a manipulative device disposed without said door, means independent of said latch bar for guiding said manipulative device in its manipulating movement, and a lock engaging said manipulative device for preventing opening of the door.
17. A locker, comprising in combination, a door frame, a door hinged therein, a latching device carried by the door, a manipulative device disposed without the door, and means engaging the manipulative device for holding it in locked relation.
18. A locker, comprising in combination, a door frame, a door hinged thereto, a staple carried by said door and having its ends disposed through the door and oppositely bent, the body of the staple outside the door being bulged to cooperate with the bent ends for holding the staple in place.
19. A locker, comprising in combination, a door frame, a door latching mechanism including manipulative devices disposed without and slidably upon the outer face of the door.

casing, the material of the door being formed to confine the contact between the manipulative device and door in a restricted area during the sliding of the manipulative device.

20. A locker, comprising in combination, a door frame, a door latching mechanism including manipulative devices disposed without and slidable upon the outer face of the casing, the material of the door being formed to confine the contact between the manipulative device and door in a restricted hidden area during the sliding of the manipulative device.

15 21. A locker, comprising in combination, a door frame, a latch manipulative device movable with respect to the door, the door being formed to confine the sliding contact to a restricted area.

20 22. A locker, comprising in combination a door frame, doors hinged to the sides thereof, and a latching bar device engageable with the top and bottom of the frame and carried by one of the doors and having 25 a lug for engaging the free edge of the other door.

23. A locker, comprising a door, a latch

bar behind said door and slidably carried thereby, a manipulating member having an end connected to the latch bar, and means on the door for guiding said manipulating device in its movement for actuating the latch bar.

24. A locker, comprising a door, a latch bar behind said door and slidably carried thereby, a manipulating member having an end connected to the latch bar, and means on the door for guiding said manipulating device in its movement for actuating the latch bar, said means being adapted to accommodate a lock for holding the parts in locked position.

25. A locker, comprising in combination a door frame, a door hinged therein, a latching device carried by the door and a manipulating device extending through the door and connected to said latching device, a keeper embracing said manipulating device and connected during its manipulative movement, said keeper and manipulative device being perforated for the reception of a lock.

WALTER N. VANCE.
